UNITED STATES PATENT OFFICE.

FRANK M. TRAINER, OF WEYMOUTH, MASSACHUSETTS.

VENDING-MACHINE.

SPECIFICATION forming part of Letters Patent No. 742,527, dated October 27, 1903.

Application filed March 22, 1902. Serial No. 99,528. (No model.)

To all whom it may concern:

Be it known that I, FRANK M. TRAINER, of Weymouth, in the county of Norfolk and State of Massachusetts, have invented a new and useful Improvement in Vending-Machines, of which the following, taken in connection with the accompanying drawings, is a specification.

My invention relates to that class of mechanisms in which the placing of a coin in a slot releases certain parts, and thus causes it to perform the desired function; and it consists in certain details of construction and arrangement by the aid of which certain functions will be performed.

The construction and arrangement may be best understood by examination of the drawings and specification.

The mechanism and operation of my apparatus are illustrated in the accompanying drawings, in which—

Figure 1 is a vertical longitudinal section taken through the center of my apparatus. Fig. 2 is a front elevation of the same. Fig. 3 is a view partly in side elevation and partly in vertical longitudinal section. Fig. 4 is a vertical cross-section taken on line X X of Fig. 1. Fig. 5 is a plan of my apparatus. Fig. 6 is a horizontal section taken on line 3 4 4 of Fig. 3, except that a part of the push-rod is shown in full, (pushed in.) Fig. 7 is a partial horizontal section showing the action of the apparatus in case a washer or disk with a hole in its center is placed in the slot. Fig. 8 is a partial horizontal section showing the action of the apparatus in case a soft (lead, for instance) disk is placed in the slot.

My apparatus is inclosed in and attached to a casing and framework, which is indicated in the drawings by the letters A A' A'', and so on.

C represents a chute in which the slot C' receives the coin which is to admit of the operation of the parts.

B is a tube mounted upon the top of the rear end of the case A and is adapted to receive the article B' B'' to be sold, and B² is the opening through which the article to be delivered is pushed.

The main operating parts of the device consist of the push-piston D, which slides in an

opening made in the head-plate A, and its attachments.

D² D⁴ constitute a moving head-piece and is connected directly to the push-piston D. 55

A small rod E is inserted in the inner end of the push-piston D and has a slight longitudinal motion, its end resting against the disk D³, which is kept in place by the spring D' in the interior of the push-piston D. The 60 said rod E has at its inner end a pin E⁶, which extends loosely through the piece L and is headed, so as to prevent the piece L from separating from it. The piece L can slide back and forth on the said pin E⁶. Thus in 65 Fig. 1 this piece L is shown at a short distance from the face of the head-piece D², and in Figs. 6, 7, and 8 it is shown in contact with the said face. The said piece L serves as a back support for the coin T and as a 70 holder for the front support K, which is pivoted at K' to it. The coin T is held between the two supports L and K, as shown in Figs. 1 and 6. The upper part D⁴ of the head-piece is inclined, so as to receive the coin as 75 it passes down the chute C' and assist in directing it into its place between the supports K and L. The front support K has an arm K³, which acts as a lever when it comes in contact with the lower part of the head-piece 80 D² and forces the front support to clamp the coin and thus assist in holding it while it is being pushed forward. The upper part D⁴ of the head-piece is made narrow, as shown in Fig. 5, and is located when the push-pis- 85 ton is forced out to its limit by the main-spring S between the two arms of the U-magnet M' M M'. (See Fig. 1.) The object of this magnet will be explained later.

A door E⁴, Figs. 3, 4, and 6, is set in the side 90 of the coin-chamber. This door swings upon a pivot (shown at its left-hand end, Fig. 6) and is closed by a spring E⁷ and in some cases locked, as will be hereinafter explained, by a locking-pin E⁸, Fig. 3. This door E⁴ is constructed to swing horizontally on a pivot, one end of which is shown near the left hand of said door, Fig. 5, and is kept normally closed by the spring E⁷. The device for locking the door E⁴ consists of a pin E⁹, Fig. 3, which will 100 drop out of locking engagement by its own weight unless held in place by the lever E'.

It is to be observed that when the forward motion of the push-piston begins the lever E' is in the position shown in Fig. 1—that is, its end is under the pin E^3 , (see Figs. 2 and 4)—
 5 and as soon as the parts advance and the pin E^6 is held back by a genuine coin then the upper end of the bent lever E' will be held back, (see Fig. 6,) causing the long end to come in contact with the pin E^3 (see Figs. 2
 10 and 4) and to throw it up, thus locking the door E^4 .

The first movement of the push-piston D will cause the coin T to move along and to meet with some frictional resistance, caused
 15 by coming in contact with the spring d , which has a tendency to force the coin (edgewise) against the opposite side of the case. This holding back of the coin at first will cause it to prevent the forward motion of the pin E^6
 20 and through it the short rod E , and as the rod E engages with the arm of the bent lever E' , pivoted at E^2 , the said lever will push against the locking-pin E^3 (see Fig. 3) and cause it to lock the door E^4 , which is otherwise yieldingly
 25 held by the spring E^7 . Now as the coin advances, being pushed by the push-piston, it cannot be forced out sidewise, as the door E^4 is locked, but will advance and engage with the projections $h' h'$ (see Figs. 1, 4, and 6) on
 30 the slide H . As soon as the coin engages with the slide H it in its continued motion forces the said slide H and its spring prolongation $H^2 H^3$ (see Fig. 1) to move toward and against the article B' to be ejected and pushes it out.
 35 During the forward movement the coin will reach the opening R and drop into any receptacle that may be provided for it. As soon as the pressure is removed from the push-piston D the spring S on the rod A^8 will, acting
 40 on the projection D^5 , force the coin-holding parts back to their original position—that is, the position shown in Fig. 1. The arm $H^2 H^3$ of the slide H is a spring and yields, so that it will draw back under the article B'
 45 next to be ejected without disturbing it and will spring up ready to take the article at its next forward movement. It should be observed that in case there is no full disk or coin in the space between the supporters L and K —that is, in the case—the slide H will not be affected by pushing in the push-piston D .

The above description relates to the working of the apparatus when a genuine coin is
 55 inserted in the slot. I will now describe the action in case a fraud is attempted. For instance, suppose an iron disk is inserted in the slot. As soon as the disk reaches the face of the U -magnet $M' M M'$ it will be stopped
 60 and held on the incline by magnet attraction and not fall into the case A' at all. When the push-piston is pushed in, the iron disk will be carried along on the incline D^4 , remaining on top of the case A , with its lower edge resting on the fixed strip A^6 resting against the part d^3 ; but as the part d^4 does

not move there will be nothing to prevent the disk from falling out of the open side. As an additional device for insuring the falling off of the iron disk I have a longitudinal strip A^6 , fixed on the top of the case A' . This strip is not on the center, but at one side, as shown in Fig. 5, so that the disk will not be balanced upon it, but will fall or roll off at one side. Another safeguard consists in the catch A^7 , which if from any cause the disk has not fallen off will catch the disk on the return of the push-piston and prevent it from falling into the slot. If a lead or other soft disk is inserted, it will as the parts are forced forward (see Fig. 8) come in contact with the spring d and be bent, so that its edge will not engage with the projections $h' h'$ on the slide H , and thus pass by without causing the slide to move. Hence no article B' will be ejected and the fraudulent disk will drop out at R . The front of the back support L is cut away, as shown in Fig. 8, to admit of bending back of the lead disk. Now suppose that a washer is dropped into the slot. It will fall into its place between the supports L and K ; but as the piston is moved forward the pin E^6 will meet with no obstruction, as it will pass through the hole in the washer. Hence the rod E will remain relatively stationary and the lever E' will not be acted upon. Hence the door E^4 will not be locked and the spring d will force the fraud washer laterally out, forcing the door E^4 open, and any further movement of the push-piston will be without effect upon the slide H . In case a disk of less diameter than the required coin is inserted then the spring d will force the said disk to one side, so that it will not engage with the projections $h' h'$ on the slide H .

The slide H is connected to the push-piston head by a wire h and the projection d' . The wire slides freely through a hole in the said projection, its end being headed or bent, so as not to become disconnected. The spring C^2 , Figs. 1 and 3, serve to prevent the passage of a coin when the head is pushed forward.

I claim—

1. In a vending-machine, a push-piston and head; coin-holder; a slide having projections constructed to engage with the edge of a genuine coin; a spring d , constructed to engage with the edge of a disk of smaller diameter than that of the genuine coin, and to force it away from the said projection; substantially as and for the purpose set forth.

2. In a vending-machine, a push-piston having a back and front coin-support attached to and constructed to move with it; a spring constructed to force the said push-piston back to its resting position; a pin yieldingly connected to the push-piston; a spring within said piston constructed to yieldingly hold said pin in place, when not opposed by a coin or unperforated disk; a door forming one side of the

passage through which the push-piston head | traverses; a locking-pin E³, constructed to engage with said door and to lock and unlock the same; mechanism constructed to operate | 5 said locking-pin; substantially as and for the purpose set forth.

In testimony whereof I have signed my

name to this specification, in the presence of two subscribing witnesses, on this 18th day of March, A. D. 1902.

FRANK M. TRAINER.
